UNITED STATES PATENT OFFICE.

CARL AXEL THEODOR SJOGREN, OF STOCKHOLM, SWEDEN.

AUTOMATIC GUN.

SPECIFICATION forming part of Letters Patent No. 739,732, dated September 22, 1903.

Application filed July 12, 1901. Serial No. 68,059. (No model.)

To all whom it may concern:

Be it known that I, CARL AXEL THEODOR SJOGREN, a subject of the King of Sweden and Norway, and a resident of Stockholm, Sweden, 5 have invented new and useful Improvements in Guns, of which the following is a specification, reference being had to the drawings accompanying and forming a part hereof.

This invention relates to improvements in guns, and has for its object to provide means by which one or more of the operations for reloading the gun and making the same ready for a new firing—such as releasing the breech, withdrawing the same, removing the empty cartridge, compressing the mainspring, forcing a new cartridge into the barrel, and bringing the breech into closed position—will be performed automatically. The firing might also be performed automatically, though the automatic firing in most instances is not desirable, because the cartridges thereby would be consumed in an instant without corresponding effect.

The invention consists, briefly, in providing in the gun one or more movable weights, heavy bodies, pistons, or the like, which on account of their inertia do not partake of the recoil of the gun, but, relative to the latter, so to speak, move forward. This movement of the weights, bodies, or the like is accomplished by suitable mechanical connections between the said weights, bodies, or the like and one or more of the mechanisms in the gun used to effect a certain function by the said mechanisms, whereby the gun may be made partly automatic, semi-automatic, or fully automatic. A weight, body, or the like arranged in a gun in accordance with my invention is movable in the longitudinal direction of the gun and slides by its movements in suitable guides. The movable weight or body may further be provided with one or more springs placed at one or both ends of the same, which springs by striking suitable shoulders or the like will store up a certain quantity of energy, which is thereupon used to effect the working of one or more mechanisms in the gun, as hereinafter more particularly described. The invention furthermore 50 consists in the combination and arrangement of parts hereinafter set forth.

In the accompanying drawings some suit-

able constructional forms of my invention are illustrated, like characters of reference referring to same or corresponding parts in all the figures.

Figures 1 and 2 show in side elevations and partial sections the parts of a gun which are necessary to illustrate the new arrangement, the locking mechanism of the breech-block 6c being shown in two different positions. Fig. 3 shows a plan view of the same part of the gun, partially in section. Fig. 4 shows in plan a somewhat modified arrangement. Figs. 5 and 6 show plans, partially in section, 6s of another form of the invention. Figs. 7 and 8 are vertical and horizontal sections of a third form of my invention.

According to Figs. 1 and 2, a weight 1 is attached to the gun so as to be movable in the longitudinal direction of the same. Said weight may suitably be located in a recess of the stock A of the gun. The rear end of said weight is connected to the center pivot of a toggle-lever 2 3, the one part 2 of which is pivoted on a fixed pin 4, whereas the other part 3 is pivotally connected to two levers 5 and 6. The rear ends of said levers form hooks 7 8, adapted to engage with corresponding projections on the breech-block 10 when the latter is in closed position, as shown in Fig. 3. The fore end of the said weight 1 is provided with a pin 9, engaging a loop 13 or the like, fixed to the barrel and serving as a guide for the said weight 1. Around the said pin 9 of the weight 1 is provided a spring 131, adapted to bring back the weight to its original position. On the breech-block 10 is also arranged a movable weight 14, sliding on the upper side of the breech-block. In suitable recesses in said weight 14 springs 15 are provided, which at their fore ends bear against projections 16 on the breech-block.

The working of the mechanism now described is the following: When the rifle in being fired recoils, the weights 1 and 14 on account of their inertia will not take part in the backward movement of the rifle, but tend to keep the same position in space, and thus move forward relative to the gun, (toward the mouth of the barrel.) The weight 1 hereby brings the toggle-lever in the position shown in Fig. 2, whereby the levers 5 6 are brought out of engagement with the breech-block 10,

the latter thus being released. While the weight 1 is releasing the breech-block the weight 14 compresses the springs 15. As soon as the recoil of the rifle ceases the springs 15 push the weight 14 backward, so that the latter by its fore end strikes the projections 16 of the breech-block and moves the same backward.

In Fig. 4 the movable weight that is connected to the locking mechanism of the breech-block is formed in the shape of a cylinder 101, surrounding the rear part of the barrel B, the rear end of said cylinder 101 being connected to the center pivot of toggle-levers 201 202, said toggle-levers being movable in the horizontal plane. Each of the parts of the said toggle-lever is pivotally connected to a two-armed horizontally-pivoted lever 505. The rear ends of these levers are, as described with reference to Figs. 1 to 3, formed as hooks adapted to engage with corresponding notches in the breech-block. The working of the modification now described is analogous with the arrangement above described.

In the modification shown in Figs. 5 and 6 only one weight 17 is provided, which is placed on the breech-block in the same manner as the weight 14. (Shown in Figs. 1 to 3.) The said weight 17 is provided with two cam-slots 18, each of which engages with one of the pins 19 20, fixed to a horizontally-pivoted two-armed lever 21 22. The said cam-slots 18 are of such form that when the weight 17 moves backward the fore ends of the levers 21 22 are turned outward. These ends of the said levers 21 22 are provided with slots 23, with which engage corresponding projections or hooks 24 when the breech-block is closed when the said pins 19 20 are about at the middle of the said cam-slots. The rear parts of the latter are parallel with the longitudinal direction of the barrel, so as to keep the said levers 21 in position when the weight 17 moves forward. In a suitable recess in the weight 17 is placed a spring 25, the fore end of which bears against a projection 26 of the breech-block. When the rifle in being fired recoils, the weight 17 on account of its inertia will move forward relative to the rifle. The spring 25 will thereby be compressed and the cam-slots be moved relative to the said pins 19 20, so that the latter will engage with the rear ends of the said slots 18. When the recoil ceases, the spring 25 will push the weight 17 backward, whereby the cam-slots 18 will disengage the levers 21 22, as shown in Fig. 6. Subsequently the weight 17 will bring the breech-block backward in the same manner as described with reference to Figs. 1 to 3.

In order that the weight 17 may not strike directly against the said projection 26 of the breech-block, it is preferable to provide also in front of the said projection a spring 27, which will take up the knock of the breech-block.

Figs. 7 and 8 illustrate a form of my inven-

tion adapted to be applied to such breech-pieces which are used in Mauser rifles. The rotatable breech-block is provided at its fore end with two projections 28, adapted to engage with a flange 29 on a part 30, attached to the barrel. The said flange 29 is provided with two slots 36, by means of which the said projections can be disengaged from the said flange 29 when the breech-block has been turned in a corresponding position. On the breech-block 31 is arranged a movable weight 32, provided with two pins 33, each engaging a spiral slot 34 of the breech-block 31. In the weight 32 two springs 35 are provided, which will be compressed when the weight moves forward on the rifle by the recoil of the same. When the recoil ceases, the weight 32 will be pushed backward, whereby the said pins 33 will be moved in the spiral slots 34, thus turning the breech-block 31 so that the projections 28 will be moved opposite the said slots 36 of the flange 29. The breech-block will subsequently be pushed backward by the weight 32 in the manner above described.

It will be easily understood by those skilled in the art that the arrangements now described may be modified in many ways without deviating from the principle of my invention. As before stated, the said weight or block may be connected by suitable gearings to any or all the mechanisms necessary for making the gun more or less automatic.

Having now described my invention, what I claim, and desire to secure by United States Letters Patent, is—

1. The combination with a gun, of a movable weight on the breech-block of the gun adapted to move forward on account of its inertia when the gun recoils, springs between the said weight and the breech-block adapted to be compressed when the former moves forward and to throw the said weight backward when the recoil of the gun ceases, means for locking the breech-block in closed position, and means for unlocking the breech-block, substantially as and for the purpose set forth.

2. The combination with a gun, of a movable weight on the breech-block of the gun adapted to move forward on account of its inertia when the gun recoils, springs between the said weight and the breech-block adapted to be compressed when the former moves forward and to throw the said weight backward when the recoil of the gun ceases, a locking mechanism for the breech-block, and mechanical connections between the said weight and the breech-block adapted to unlock the latter when the said weight moves backward, substantially as and for the purpose set forth.

In testimony whereof I have hereunto subscribed my name in the presence of two subscribing witnesses.

CARL AXEL THEODOR SJOGREN.
